UNITED STATES PATENT OFFICE.

LEWIS E. WATERMAN, OF ROCKFORD, ILLINOIS, ASSIGNOR TO EMERSON-BRANTINGHAM COMPANY, OF ROCKFORD, ILLINOIS, A CORPORATION OF ILLINOIS.

PLOW.

1,229,354.

Specification of Letters Patent. Patented June 12, 1917.

Original application filed December 16, 1915, Serial No. 67,202. Divided and this application filed April 29, 1916. Serial No. 94,419.

To all whom it may concern:

Be it known that I, LEWIS E. WATERMAN, a citizen of the United States, residing at Rockford, in the county of Winnebago and State of Illinois, have invented certain new and useful Improvements in Plows, of which the following is a specification.

This invention relating to wheeled plows is a division of my application Serial No. 67,202, filed Dec. 16, 1915, and has more particular reference to the means employed for raising and lowering the rear end of the plow-carrying frame.

In plows of this character it is desirable to raise and lower both the front and rear ends of the frame to carry the plows into and out of the ground. The rear end of the frame is raised and lowered upon and with respect to the rear furrow wheel, which, it is desired, shall be automatically changed from a caster wheel to a fixed wheel upon movement of the frame to raised and lowered positions, respectively.

My invention aims, primarily, to provide an improved mounting for the rear furrow wheel whereby the wheel will be automatically and positively locked against castering when the frame is lowered and will be permitted to caster against a resiliently yieldable pressure when the frame is raised. Thus the rear furrow wheel is held rigidly in relation to the plow during the plowing operation so as to hold the plows in line with the draft and effectively resist the side thrust of the plows, but when the plows are raised is permitted to caster against a spring resistance when turning a corner, the resistance being such that the wheel will not swing too freely or easily turn when backing the plow.

Referring to the drawing—

Figure 1 is a side view of my improved rear furrow wheel mounting and operating means, attached to a plow-carrying frame, showing the same in raised position;

Fig. 2 is a view of my improvements showing the plow-carrying frame in lowered position;

Fig. 3 is a view of the furrow wheel spindle mounting, with the upper end thereof in section; and

Fig. 4 is a plan view of the parts shown in Fig. 3.

Since this invention pertains solely to the

mounting and control of a plow furrow wheel, I have deemed it unnecessary to illustrate an entire plow and consequently have shown the improvements in connection with only a portion of a plow-carrying frame on beam 5. It should also be understood that while my improvements are designed for use especially in connection with wheeled plows having power lift mechanism for raising the front end of the plow-carrying frame such as described in the above mentioned application, any operating mechanism may be employed in place of power lift mechanism.

Referring to the drawing, the rear furrow wheel 6 may be suitably mounted on an inclined axis on a spindle 7 so as to tread in the corner of a furrow as and for a purpose well understood in this art. The upright portion 8 rotatably mounted in a sleeve bracket 9 is held against axial movement therein by means of a collar 11 secured by a set screw 12 to the upper end of the spindle portion 8 and shaped to fit over an annular flange 13 integral with the upper end of the sleeve bracket 9, as shown in Fig. 3. The collar 11, while permitting rotative movement of the spindle in the sleeve bracket, prevents the spindle from moving longitudinally with respect to the bracket. The bracket is pivotally mounted adjacent to its lower end at 14 upon a plate 15 bolted fixedly to and extending rearwardly from the rear end of the plow beam 5 so as to be capable of rocking backwardly and forwardly on its pivot to raise and lower the rear furrow wheel with respect to the plow beam. A laterally projecting guide 16 integral with the sleeve bracket slidably engages the landward side of the plate 15 so as to hold the bracket 9 against lateral displacement. The upper rear edge of the plate 15 is shaped in the form of an arc struck from the center of the pivot bolt 14 so that the guide 16 will co-operatively engage the plate 15 as the bracket 9 is swung on its pivot. A lever 17 pivoted intermediate its ends at 18 to the plate 15 is arranged so that its lower end 19 is disposed intermediate the arms of a forked abutment 21 integral with the bracket 9 and engages the said abutment to hold the bracket 9 and spindle 7 in substantially upright position as shown in Fig. 1. A rod 22, the forward end of which (not

shown) may be attached to a suitable operating mechanism holds the lever 17 in the position shown in Fig. 1. The said rod 22 passes through an eyelet 23 swiveled to the 5 upper end of the lever 17 and is equipped with a set collar 24 that abuts against the said eyelet.

When the rod 22 is moved rearwardly, thereby releasing the lever 17, the rear end 10 of the plow frame will be lowered by gravity as the bracket 9 swings from the position shown in Fig. 1 to that shown in Fig. 2. This swinging movement of the sleeve 9 is limited by engagement of the collar 11 15 with the lever 17, the collar being shaped to provide a recess 25 for the reception of the lever 17. Since the walls of the recess 25 engage both sides of the lever 17 and the collar 11 is fixedly secured to the spindle 8, it will be apparent that when the spindle 20 is swung forwardly to the position shown in Fig. 2, it will be positively locked against rotation. Thus when the plow frame is lowered, the rear furrow wheel becomes automatically locked against castering, so that 25 when the plow is in operation the rear furrow wheel will be held rigidly at the proper angle in the furrow to effectively carry the side thrust from the plow.

30 When the plows are raised, it is desirable that the rear furrow wheel be permitted to caster, although not too freely, since when moving the plow forwardly and backwardly the rear furrow wheel might caster and 35 swing the plow to one side, this being more apt to occur when backing the plow. To provide against entirely free castering of the rear furrow wheel, a spring resistance is employed to yieldingly oppose castering 40 movements. The means illustrated for accomplishing this purpose consists of an arm 26 pivoted at 27 to the rear side of the sleeve bracket 9 and provided at its upper end with a flat forward face 28 which is urged 45 into engagement with an opposed flat face 29 formed on the collar 11 by an expansion spring 31, the ends of which are confined between the outer end of said arm 26 and a nut screwed on a bolt 32 which is connected 50 to the sleeve bracket 9 at 33.

From the foregoing, it will be apparent that I have provided a very simple and effective means whereby the rear end of a plow frame may be raised and lowered and 55 the rear furrow wheel automatically and positively locked against castering when the frame is lowered and yieldingly held against castering when the frame is raised.

I claim:

60 1. In a plow, the combination of a plow-carrying frame, a sleeve bracket pivotally mounted on the frame on a horizontally disposed axis, a spindle journaled in said sleeve bracket so as to caster on an upright 65 axis, a furrow wheel mounted on the lower

end of the spindle, a lever pivoted on the frame and coöperable with the sleeve bracket so as to rock the same on its pivot by movement of the lever, and means connected with said spindle adapted to be brought into 70 locking engagement with the lever to prevent rotative movement of the spindle in the sleeve bracket when the frame has been moved to lowered position.

2. In a plow, the combination of a plow-carrying frame, a furrow wheel, means connecting the furrow wheel to the frame so that the furrow wheel may caster about an upright axis and may be moved to raised and lowered positions with respect to the 80 frame, a lever mounted on the frame and co-operating with said means to effect movement of the wheel to said raised and lowered positions, and means operating between the 85 lever and wheel-connecting means for automatically locking the wheel against castering when the wheel has been moved to raised position.

3. In a plow, the combination of a plow-carrying frame, a rear furrow wheel, an upright spindle upon the lower end of which the furrow wheel is mounted, means connecting the spindle to the frame in such manner as to permit the spindle to rock 90 backwardly and forwardly on a horizontally disposed axis located intermediate its ends and to allow the wheel to caster about the longitudinal axis of the spindle, a lever pivoted on the frame and arranged to coöperate with said means for moving the spindle about said horizontal axis and means 95 operable between the spindle and said lever for locking the spindle to prevent castering 100 when the wheel has been raised with respect to the frame.

4. In a plow, the combination of a plow-carrying frame, an upright sleeve bracket pivotally mounted thereon to swing forwardly and backwardly relatively thereto, a 110 spindle journaled in the sleeve bracket, a furrow wheel mounted on the lower end of the spindle, a lever pivoted on the frame and engaging the sleeve bracket for rocking the same on its pivot, means fixed to the spindle 115 for engaging said lever when the furrow wheel has been moved to raised position with respect to the frame and thereby serving to lock the spindle to prevent castering and for disconnecting from said lever when the wheel has been moved to lowered position, a part pivoted on the sleeve bracket, a 120 part secured to the spindle and coöperating with said pivoted part, and means yieldingly urging the pivoted part into engagement with the other part to yieldingly hold 125 the spindle against rotation in the bracket.

5. In a plow, the combination of a plow-carrying frame, an upright sleeve bracket pivotally mounted thereon to swing forwardly and backwardly relatively thereto,

a spindle journaled in the sleeve bracket, a furrow wheel mounted on the lower end of the spindle, a lever pivoted on the frame and engaging the sleeve bracket for rocking 5 the same on its pivot, means fixed to the spindle for engaging with the lever when the furrow wheel is moved to raised position with respect to the frame whereby to prevent rotative movement of the spindle in its 10 bracket and to be released from said lever when the wheel is lowered, and means coöperating between the bracket and spindle for yieldingly resisting rotative movement of the spindle in the bracket.

15 6. In a plow, the combination of a plow-

carrying frame, an upright sleeve bracket pivotally mounted thereon so as to swing forwardly and backwardly with respect thereto, a spindle rotatably mounted in the bracket, a furrow wheel mounted on the 20 lower end of the spindle, a lever pivoted intermediate its ends on the frame, the lever coöperating on one side of its pivot with the bracket to effect said swinging movement thereof by rocking of the lever, and means 25 on the spindle for engaging the lever on the opposite side of its pivot to lock the spindle against rotation.

LEWIS E. WATERMAN.
